No. 799,930.

PATENTED SEPT. 19, 1905.

J. E. NITKEY.
RAILWAY SWITCH.
APPLICATION FILED APR. 6, 1905.

UNITED STATES PATENT OFFICE.

JOHN E. NITKEY, OF NEW LONDON, WISCONSIN.

RAILWAY-SWITCH.

No. 799,930.

Specification of Letters Patent.

Patented Sept. 19, 1905.

Application filed April 6, 1905. Serial No. 254,078.

To all whom it may concern:

Be it known that I, JOHN E. NITKEY, a citizen of the United States, residing at New London, in the county of Waupaca and State of Wisconsin, have invented certain new and useful Improvements in Railway-Switches; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to railway-switches; and the main object of the invention is to provide means whereby any train approaching a switch will automatically throw the switch into a safe and proper position for that train, so that it becomes impossible for any train to get wrecked by running into the switch while it is "open." This object I attain by the novel construction and combination of parts illustrated in the accompanying drawings, in which—

Figure 1 is a top or plan view of a piece of railroad having a switch embodying my improvements. Fig. 2 is a side elevation of Fig. 1, and Fig. 3 is an enlarged top view of 30 the pulley 13 in Figs. 1 and 2. Fig. 4 is a modification of the parts 35 36 in Fig. 2.

Referring to the drawings by reference-numerals, 1 designates the ties, and 2 the rails, forming the main track or road, while 3 designates the rails of a branch line or side track.

4 designates the usual switch-tongues or ends of the rails, which are moved horizontally in throwing the switch. These tongues may be tapering, as shown, or may be of the 40 common kind running the regular size and form of the rail to its very end and made movable into line with similar ends of the main track and with the side track, as may be required. In either case the moving rails or 45 tongues are braced together by one or more braces 5 and operated by a switch-bar, which by a pitman or link 7 is connected with the crank 8, provided at the lower end of the usual upright 9, oscillating in the stand 10, secured upon the ends of the ties, or may be secured to the ground in any suitable manner.

11 is the usual crank for switching by hand, and 12 is the well-known signal-plate.

Projecting from the foot-piece 10^a of the 55 stand 10 are stops 10^b, which stop the motion

of the crank 8 when it is slightly over its "dead-center" or linear position with the link 7, thus locking the switch against accidental motion from side pressure by the car-wheels when the switch may be on a curve of 60 the road and preventing the crank from turning too far in either direction.

Upon a suitable point of the standard 9 is fixed a pulley 13, to which is fixed one end of each of the three chains or cables 14, 15, and 16, which are operated by the means I will now describe.

A suitable distance—say a thousand feet—from the switch the main track is provided with a transverse rock-shaft 17, having at one 70 end a rocker-arm 18, operated by a chain, cable, or rod 19 and a rocker-arm 20 of a rock-shaft 21, journaled at 22, and having another rocker arm or crank 23, operated by a downwardly-pressing lever 24, pivoted at 25 and arched 75 upward between its ends, as shown in dotted lines 24 in Fig. 2. A similar rock-shaft 21^a and lever 24^a are provided at the side of the side track 2 and secured by its arm 20^a to the chain 16. The shaft 17 is at its opposite end 80 provided with two opposite rocker-arms 26 27, connected, respectively, with the chains or cables 14 and 15. The shaft 17 is also provided with two oppositely-placed cranks 28 and 29, upon which rest, respectively, the 85 arched levers 30 31, which are pivoted with one end, as at 32, to the rails or any other stationary object.

In Fig. 2, 33 represents a portion of either a locomotive or car of the train, of which 34 90 is one of the regular carrying-wheels, while 35 is a special small wheel carried by a bracket 36, affixed to the car or locomotive. The wheel 35 on the train running on the main line 2 is placed to run over and depress either 95 the lever 31 or the lever 24, according to the direction from which the train is coming. The result of the depression of either of said levers will be to throw the switch so that the main track is clear for said train to pass the 100 switch; but if a train belonging to the side track 3 comes along its wheel 35, being arranged farther out to the side, will depress either the lever 24^a or the lever 30, and thereby turn the standard 9 so as to throw the 105 switch into proper position to connect the side track 3 with the main track.

Any person skilled in the art to which this invention appertains will readily understand from the above description how the invention 110

operates and the functions of the chains, cables, or rods 14, 15, and 16. Only this may be added, that 37 designates posts with sheaves 38 for the support of said chains or rods and 5 that the chains are secured with their ends to the pulley 13 at such points that they never unwind fully from the pulley, but will always extend in a tangent position to either the outer side of the pulley or its inner side near 10 the track. This keeps the chains always taut and enables the pulley to oscillate about half a turn, while the cranks 23, 28, and 29 need to be turned only a few degrees by the levers resting on them.

15 It is evident that a pulley may easily be substituted for the radial arms 26 27, if so desired.

In Fig. 4 is shown how, instead of the single wheel 35 in Fig. 2, two wheels 35^a and 35^b 20 may be mounted on studs, one at the inner and the other at the outer side of the horizontal arms 39 of a hand-lever 40, pivoted at 41 to the bracket 36^a, so that when its upper end is sprung into the notch 42 of the segment 43, 25 fixed on the car or locomotive, the wheel 35^a is held down, so as to operate the lever 31 of the switching mechanism, and if the lever 40 be interlocked in the notch 42^a the wheel 35^b 30 will ascend and the wheel 35^a will descend and be ready to depress the lever 30. This arrangement enables the train while in full motion to decide on which track to switch in upon and to throw the switch accordingly before coming to it by simply setting the lever 35 40 in the right position.

Having thus described my invention, what I claim, and desire to secure by Letters Patent, is—

1. In a railway-switch, the combination 45 with the moving ends of the rails and the switch-bar 6, pitman or link 7, crank 8 and oscillating crank-shaft 9 extending therefrom, of a pulley secured on said shaft and cables or chains 14 and 15 secured each with one end 50 to the face of the pulley and always extending in a tangent position from opposite sides of the pulley; the rock-shaft 17 journaled transversely below the top of the main rails and having the cranks 28 29, the arched levers 30 31 pivoted each at one end to a fixed 55 point and resting upon the cranks, the rocker-arms 26, 27 at the end of said shaft and connected with the chains or cables 14 15, and wheels carried by the trains in positions to press down either the lever 30 or 31, and means for stopping the crank 8 when turned into either of the two desired positions.

2. In a railway-switch, the combination 60 with the moving ends of the rails and the switch-bar 6, pitman or link 7, crank 8 and oscillating crank-shaft 9 extending therefrom, of a pulley secured on said shaft and cables or chains 14 and 15 secured each with one end 65 to the face of the pulley and always extending in a tangent position from opposite sides

of the pulley; the rock-shaft 17 journaled transversely below the top of the main rails and having the cranks 28 29, the arched levers 30 31 pivoted each at one end to a fixed point and resting upon the cranks, the rocker-arms 26, 27 at the end of said shaft and connected with the chains or cables 14 15, and wheels carried by the trains in positions to press down either the lever 30 or 31, and means for stopping the crank 8 when turned into either 75 of the two desired positions, and the rocker-arm 18 at the other end of the shaft 17, the rock-shaft 21 with arms 20 and 23, the lever 24 arranged near the main rails and resting on said crank or arm 23, and a cable, chain or rod connecting the arms 18 and 20.

3. In a railway-switch the combination 80 with the moving ends of the rails and the switch-bar 6, pitman or link 7, crank 8 and oscillating crank-shaft 9 extending therefrom, 85 of a pulley secured on said shaft and cables or chains 14 and 15 secured each with one end to the face of the pulley and always extending in a tangent position from the opposite sides of the pulley; the rock-shaft 17 journaled transversely below the top of the main rails and having the cranks 28 29, the arched levers 30 31 pivoted each at one end to a fixed 90 point and resting upon the cranks, the rocker-arms 26, 27 at the end of said shaft and connected with the chains or cables 14 15, and wheels carried by the trains in positions to press down either the lever 30 or 31, and means for stopping the crank 8 when turned into either 95 of the two desired positions, and 100 the rocker-arm 18 at the other end of the shaft 17, the rock-shaft 21 with arms 20 and 23, the lever 24 arranged near the main rails, and resting on said crank or arm 23, and a cable, chain or rod connecting the arms 18 105 and 20, and the lever 24^a pivoted adjacent to the side track or branch road, the rock-shaft 21^a having one rocker-arm operated by said lever and a second rocker-arm 20^a, and the chain or other connecting line between the 110 latter arm and the pulley 13, so as to operate the same, substantially as set forth.

4. In a railway-switch the combination 115 with the moving ends of the rails and the switch-bar 6, pitman or link 7, crank 8 and oscillating crank-shaft 9 extending therefrom, 120 of a pulley secured on said shaft and cables or chains 14 and 15 secured each with one end to the face of the pulley and always extending in a tangent position from opposite sides 125 of the pulley; the rock-shaft 17 journaled transversely below the top of the main rails and having the cranks 28 29, the arched levers 30 31 pivoted each at one end to a fixed point and resting upon the cranks; the rocker-arms 126, 27 at the end of said shaft and connected with the chains or cables 14 15, and wheels carried by the trains in positions to press down either the lever 30 or 31, and means for stopping the crank 8 when turned into either 130

of the two desired positions, said wheels on the train being two in number, a lever pivoted to the train and carrying one wheel in line with each of the switch-levers 30 31, and 5 means for holding either of the two wheels downward so as to engage one of the levers, substantially as and for the purpose set forth.

In testimony whereof I affix my signature in presence of two witnesses.

JOHN E. NITKEY.
